United States Patent Office

Des. 222,267
Patented Oct. 12, 1971

222,267

TELEPRINTER OR THE LIKE

Robert J. Ramig, Jr., Niles, Ill., assignor to Teletype Corporation, Skokie, Ill.

Filed Aug. 19, 1970, Ser. No. 24,585

Term of patent 14 years

Int. Cl. D14—02

U.S. Cl. D26—5

FIG. 1

FIG. 2

FIG. 3

FIG. 1 is a front perspective view of a teleprinter showing my new design;

FIG. 2 is a right side view thereof; and

FIG. 3 is a rear view thereof.

I claim:

The ornamental design for a teleprinter or the like, substantially as shown.
